TOOL HANDLE

Edmond Bachtold, Whitewood, Saskatchewan,
Canada

Application April 1, 1935, Serial No. 14,164

1 Claim. (Cl. 30—151)

My invention relates to improvements in bush tools and an object of my invention is to provide a bush tool comprising in combination, an axe, a wood saw, a carcass saw, a huntsman's knife, a pick, a penknife, a thermometer, a compass, a nail puller, a hammer and which has space provided for such useful articles as concentrated food, medical accessories, etc.

With the foregoing more important objects in view and such other minor objects as may appear as the description proceeds, my invention consists in the construction and arrangement of parts, all as hereinafter more particularly described, reference being had to the accompanying drawings, in which:

Fig. 1 is a side elevation of my tool showing portions of the shaft and handle broken to illustrate the instruments carried therewithin.

Fig. 2 is a side elevation of my device.

Fig. 3 is a cross section taken on the line 3—3 of Figure 1.

Fig. 4 is a cross section taken on the line 4—4 of Figure 1.

Fig. 5 is a plan view of the axe head.

Fig. 6 is a detail upon the line 6—6 of Figure 5.

Fig. 7 is a plan view of my compass.

Fig. 8 is a cross section similar to Figure 3 but showing the rings rotated and the keys bearing against the shank.

In the drawings like characters of reference indicate corresponding parts in the different figures.

My invention consists of a hollow shaft 1 which will preferably be made of metal, one end of said shaft terminating in an axe head 2. The axe head is provided with a small notch 3 for the purpose of drawing nails, etc. and a flattened rear face 4 for use as a hammer.

Below the projecting hammer portion, is a recess 5, the recess being provided with side walls 6 drilled to receive a stud 7. A pick 8 is pivoted upon this stud, the pick being rabbeted as at 9 to fit into the recess 5. When the pick is in use, it may be extended as shown in Figure 1 and when not in use, may be swung against the shaft as shown by the phantom lines in the same figure.

As before mentioned, the shaft 1 is hollow and encased therewithin is a blade 10, one edge of which is provided with wood saw teeth 11 and the opposite with fine teeth 12 for the purpose of cutting the bone of a carcass, etc. while adjacent both ends of the blade are recesses 13 and 13', 14 and 14'.

The shaft 1 is substantially oval in cross sec-

tion, longitudinal grooves 15 being disposed through a substantial length on either side of same at the edges of the major longitudinal axis. Within these grooves are located flat spring members 15' which are secured to the shaft at the point 16 by means of pairs of rivets 17. At a point approximately half way along the spring members 15' are studs 18, these being designed to bear against the edges of the saw blade to prevent movement thereof.

Adjacent the ends of the springs are further inwardly projecting studs 19 of somewhat greater length than the studs 18 while a still further pair of rotatable studs 20 are located adjacent the studs 19. These studs extend into the recesses 14 and 14' upon the end of the saw blade. Finger rings 21 are attached to the studs 20 extending through small lateral drillings therewithin. Keys 21' extend through drillings formed laterally through the inner end of the studs 20 for the purpose presently to be described.

A hunting knife 22 is receivable within the shaft 1 and is designed to extend alongside the blade in the manner best shown in Figure 1 and Figure 3, the handle 23 of this knife extending beyond the end of the shaft 1. It will be noted that the lower end of the handle 23 is spread out as at 24 as is usual in hunting knives and these projections are receivable through orifices 25 adjacent the end of the springs 15' to prevent withdrawal of the knife until desired.

The handle of the knife is hollow and is divided by a partition 26. Upon one side of the partition a small penknife or jack-knife 27 may be housed and the other side of the partition is provided with an arcuate guard 28 into which may be slid a thermometer 29. This guard should preferably be lined with felt and should snugly fit over the thermometer to prevent breakage in the event of its being jarred.

The handle is finally covered by a screw threaded cap 30 upon the inside of which is attached a compass 31.

The widest portion of the head 2 is of a hollow formation and divided into a plurality of compartments 32 within which may be housed if desired tubes 33 for the containing of concentrated food, surgical accessories, etc. The compartment is capped by a sliding cover 34 which is preferably provided with an oblique and bevelled face 35 and upon the under side of this cover is a light spring 37 to maintain the cover in place, the cover being attached and pivoted to the axe head by means of a stud 38.

It will finally be noted that I have provided

small slots 39 parallel to the axis of the handle upon one side of the orifices through which the studs 20 extend. These slots are provided to permit the passage of the key or pin 21' there-
5 through, when the springs are drawn outwardly or sprung inwardly.

In order to withdraw the hunting knife from the sheath, the studs 20 are rotated by means of the rings 21 until the pins 21' are parallel to
10 the slots 39. The studs are then pulled outwardly, at which time, the pins will contact with the under side of the spring leaves 15'. Further outward movement of the studs will cause these leaves to distend and the orifices 25 will disengage from the projecting portions 24 of the knife handle, thus permitting removal thereof.

When it is desired to draw out the saw blade, the extreme end which extends far enough out of the shaft for the purpose, is grasped between the
20 finger and thumb and pulled outwardly. When the pairs of studs 19 and 20 are in alignment with the pairs of recesses 13 and 13', the rings are turned at right angles again so that the keys 21' will slip into the groove 15 and the studs extend
25 into the recesses 13 and 13'. To replace the blade and the knife in the sheath, it will be again necessary to draw out the rings as before and then push the blade down into the shank 1 afterwards nesting the hunting knife blade 22 in place
30 beside the saw and then releasing the springs provided by turning the rings back to their normal position.

It will be finally noted that I have provided small longitudinal slots 39 upon one side of the

orifices through which the studs 20 extend, these slots being for the purpose of permitting the passage of the key 21' therethrough when the springs are drawn outwardly or sprung inwardly.

From the foregoing, it will be seen that I have provided a very compact and useful bush tool containing in a limited space a variety of objects extremely useful for hunters, prospectors and others concerned with bush conditions.

Since various modifications can be made in the above invention, and many apparently widely different embodiments of same, made within the scope of the claim without departing from the spirit and scope thereof, it is intended that all 15 matter contained in the accompanying specification shall be interpreted as illustrative only and not in a limiting sense and I desire only such limitations placed thereon as are specifically expressed in the accompanying claim.

What I claim as my invention is:—

Improvements in tool handles comprising a tubular sheath to receive a cutting instrumentality, a projection on said instrumentality extending at right angles thereto and at a point above the open end of the sheath, a spring leaf extending along the outer surface of the sheath and in a plane of said projection and provided with an orifice adjacent one end thereof, said orifice being adapted to receive said projection and means for spacing a portion of said leaf from said handle to permit disengagement of said instrumentality.

EDMOND BACHTOLD.
